FUEL CONTROL MEANS

Donald S. Hersey, West Hartford, Conn., assignor to United Aircraft Corporation, East Hartford, Conn., a corporation of Delaware

Application December 14, 1940, Serial No. 370,160

21 Claims. (Cl. 123—140)

This invention relates to improvements in means for supplying a regulated quantity of fuel to an engine, such as an internal combustion engine, and has for an object the provision of a simplified, light weight mechanism for accurately metering the engine fuel to maintain the desired fuel-air ratio for the engine intake under various engine operating conditions.

A further object resides in the provision of means effective to accurately and continuously detect the density of the engine intake air and to meter the engine fuel supply in accordance with the product of the density and volumetric rate of flow of the intake air.

Other objects and advantages will be more particularly pointed out hereinafter or will become apparent as the description proceeds.

In the accompanying drawing, in which like reference numerals are used to designate similar parts throughout, there is illustrated a suitable mechanical embodiment for the purpose of disclosing the invention. The drawing, however, is for the purpose of illustration only and is not to be taken as limiting or restricting the invention as it will be apparent to those skilled in the art that various changes in the illustrated arrangement may be resorted to without in any way exceeding the scope of the invention.

In the drawing,

Fig. 1 is a diagrammatic illustration of an engine fuel control apparatus constructed according to the invention, and

Fig. 2 is a longitudinal sectional view of an air density detecting device constituting a portion of the fuel control apparatus shown in Fig. 1.

Referring to the drawing in detail, and particularly to Fig. 1, the numeral 10 generally indicates an internal combustion engine which may be a radial air-cooled type of engine, such as is conventionally employed for the propulsion of aircraft, although the invention is in no way limited to any particular type of internal combustion engine. Such an engine may have a crankcase portion, as indicated at 12, upon which are mounted a number of cylinders, one of which is indicated at 14, and may have a supercharger section 16 having an air intake duct 18 leading to an impeller 20 which discharges into a diffuser section 22 connected with the various cylinders by suitable means, such as the individual intake pipes, one of which is indicated at 24. Fuel may be supplied to the engine through an injection nozzle 26 which distributes the fuel into the intake air stream entering the impeller 20 so that the fuel is thoroughly mixed with the intake air as the air and fuel pass through the impeller and the diffuser 22.

The intake air may be constantly sampled and its density continuously detected by a density de-

tecting apparatus, generally indicated at 28 and particularly illustrated in Fig. 2.

As will presently be described, variations in the density of the intake air produce variations in the pressure differential between the conduits 30 and 32 which lead from the device 28 to a pneumatic motor device, generally indicated at 34. The device 34 comprises a generally cylindrical casing 36 divided into two substantially equal chambers by a flexible transverse partition 38. The conduit 32 is connected with the chamber, as indicated at 40, at one side of the diaphragm 38 while the conduit 30 is connected with the chamber, as indicated at 42, at the opposite side of the diaphragm. A rod 44 is operatively connected with the diaphragm 38 and is connected to the casing 36 by suitable flexible seals, as indicated at 46 and 48, in such a manner that a pressure differential between the chambers 40 and 42 acting upon the diaphragm 38 will move the rod 44 in one direction or the other and changes in the pressure of the atmosphere surrounding the casing will not affect the force exerted by the diaphragm 38 because of the balancing effect of the substantially equal areas of the flexible seal members 46 and 48.

One end of the rod 44 is connected to a control ring 48 of a variable displacement fluid pump, generally indicated at 50, and the other end 30 passes through a compression spring 51 which presses against the diaphragm 38 and casing 34 and resiliently urges the rod 44 in a direction to decrease the displacement of the pump 50. If desired, a servomotor may be interposed between 35 the rod 44 and the pump control ring. The pump 50 has an intake 52 which may be connected with the fuel tanks of a vehicle, such as an airplane, and an outlet 54 connected with the inlet of the fuel nozzle 26. Between the inlet and outlet there is an engine driven rotor 56 carrying a plurality of radially disposed vanes 58 which rotate in the member 49 and pump fluid, such as fuel, from the pump intake 52 to the pump outlet 54 whenever the member 49 is positioned eccentrically with respect to the rotor 56. As the rod member 44 moves to change the eccentricity of the member 49 relative to the rotor 56 the pump displacement for each revolution will be varied from substantially zero when the two members 45 are exactly concentric to the maximum displacement when the member 49 reaches its position of maximum eccentricity with respect to the member 56.

As the pump is driven by the engine at some 55 constant ratio to engine speed, the output of the pump would normally vary in direct proportion to the speed of the engine for any fixed position of member 49, and the fuel supply to the engine would then be a direct function of 60 engine speed. The control unit 28 modifies the

displacement of the pump 50 in accordance with variations in density of the engine intake air so that the output of the pump becomes a function of the product of engine speed and intake air density to maintain the engine fuel supply at a substantially constant proportion to the engine air supply as will be explained in greater detail hereinafter.

The characteristics of unit 28 may be modified so that the output of the fuel pump becomes a function of the product of the engine speed and the charge density and the volumetric efficiency of the engine.

With this arrangement, if the engine speed is unchanged during a change in density, as by changing the altitude of the airplane or by throttling at the intake air entrance, the fuel supply will be changed, and, in the event the density of the intake air decreases under these conditions, the fuel supply will be accordingly diminished while, if the density of the intake air is increased, as by opening the throttle 60, while maintaining the engine speed constant, as by means of a controllable-pitch propeller, the fuel supply will be increased to meet this increased engine power condition.

The density detecting device generally indicated at 28 may be a device such as is particularly illustrated and described in my co-pending United States application Serial No. 311,153, filed December 27, 1939, for Density measuring devices, and may include a constant displacement pump 62, such as a "Roots blower," driven from the engine at a constant ratio to engine speed by some suitable means, such as the flexible drive 64. One side of this pump is connected with the air intake duct 18 through a suitable branch conduit 66 and the other side is connected with the interior of a chamber 68 which is connected with an adjoining chamber 70 through a fixed orifice 72 provided in a transverse partition 74 separating the two chambers. The conduit 66 is connected to the engine intake system between the throttle 60 and the engine cylinders so that density variations in the air supplied to the cylinders occasioned by operation of the throttle will be imposed on the fuel regulating device and the chamber 70 is connected with the air intake duct 18 through a branch channel 76 spaced from the channel 66. The effective area of the orifice 72 is controlled by a movable plug 78 which is urged towards orifice closing position by means of a coiled compression spring 80 and is moved to orifice opening position by centrifugal force exerted on flyballs 82 driven from the pump shaft 84 through a suitable gear train, generally indicated at 86. The plug shaft 88 may extend beyond the orifice and into a guide 90 provided with a stop 92 to prevent the plug from entirely closing the orifice at any time. With this arrangement the pressure differential between the chambers 68 and 70 will be proportional to the density of the air flowing through the air intake duct 18 since the pressure head necessary to force a constant volume of air through a constant orifice varies as the air density and this relation is maintained in the present apparatus by varying the orifice directly as the air volume varies with variations in the speed of the constant displacement pump. This pressure differential will be transmitted through the conduits 30 and 32 to the fluid motor 34 to adjust the displacement of the pump 50 in accordance with variations in the density of the engine intake air. Suitable

means may be provided, if desired, to richen the mixture at high engine power rates with accompanying high speed to protect the engine, and to meter automatically the fuel for engine idling operation. This may be conveniently accomplished by giving the movable plug 78 a contour such that the area of the opening between the side of this plug and the edge of the orifice 72 will be varied in a predetermined manner with variations in the engine speed.

The contour of the plug 78 may also be designed to compensate for changes in the volumetric efficiency of the engine with changes in engine speed so that, if the volumetric efficiency decreases above a particular speed, the contour of the plug will proportionately modify the rate of change of the opening between the plug and the orifice 72 as the engine speed increases above the particular rate. The device might also be compensated for variations in the volumetric efficiency of the engine in other ways such as by selecting a suitable variable rate spring of proper characteristics for the spring 80, or by providing an additional orifice through the partition 74, a plug for varying the area of the additional orifice and an engine speed responsive governor for controlling the plug.

A manual mixture control may be incorporated by providing a connecting channel 94 between the channels 30 and 32 and intercepting this connecting channel with a manually controllable valve 96. With this arrangement the fuel mixture can be leaned out by controlling the valve 96 to provide a bleed connection between the channels 30 and 32 thereby reducing the pressure differential on the opposite sides of the diaphragm 38 and permitting the spring 51 to reduce the capacity of the fuel pump.

The air may flow through the device 28 in either direction but, for certain installations, it has been found desirable to have the blower 62 draw the air through the chambers 70 and 68 rather than force it through. The air from the duct 18 would then flow through the channel 76 to the chamber 70, through the orifice 72 to the chamber 68, then through the blower 62 and back to the duct through the channel 66. Under these conditions, if the engine were rapidly accelerated there would be a sudden increase in the pressure above the diaphragm 38 which might result in an over rich mixture being temporarily supplied to the engine. This condition can be controlled by providing in the line 32 a restriction, as indicated at 98, properly dimensioned to retard the transmission of the pressure rise in the chamber 70 to the upper side of the diaphragm 38. This provides a means of controlling the fuel charge during acceleration of the engine.

If desired, a pressure type gauge 100 may be connected between the lines 30 and 32 to indicate the pressure head across the orifice 72. If the orifice varying plug then varies the orifice in such a manner that the pressure head across the orifice is proportional to the product of intake air density and volumetric efficiency of the engine, the gauge dial can be calibrated to read in units of indicated mean effective pressure which is an empirical measure of the mean working pressure of the gas on the engine pistons. Also, the gauge dial can be calibrated to read in suitable units which, when multiplied by a term representing engine speed, will indicate the rate of fuel flow to the engine.

While a suitable mechanical embodiment has been illustrated in the accompanying drawing

and hereinabove described for the purpose of disclosing the invention, it is to be understood that the invention is not limited to the particular arrangement so illustrated and described but that such changes in the size, shape and arrangements of the various parts may be resorted to as come within the scope of the subjoined claims.

Reference is made to my copending application Serial No. 311,153 (filed December 27, 1939), which shows and claims subject matter shown 10 and not claimed in this application.

Having now described the invention so that others skilled in the art may clearly understand the same, what it is desired to secure by Letters Patent is as follows:

1. Means for supplying fuel to an engine, having an air intake duct, in a predetermined proportion to the weight of air flowing through said duct per unit of time comprising, a fluid pump having a definite volumetric capacity for each operating speed, a fluid conduit connected with said pump and said air intake duct, an orifice in said conduit for establishing a pressure differential proportional to the fluid density, means for varying the area of said orifice in accordance with the speed of said pump to render said pressure differential proportional to air density regardless of pump speed, an engine driven controllable displacement fuel pump, and fluid pressure responsive means actuated by said pressure differential for varying the displacement of said fuel pump in accordance with variations in the density of the engine intake air.

2. In combination with an engine having an air intake duct and a fuel supply, means for proportioning the amount of fuel supplied to said engine to the weight of engine intake air flowing through said intake duct per unit of time comprising, an engine driven fluid pump having a definite volumetric capacity for each operating speed connected at both sides to said intake duct, a restriction in the connection at one side of said pump, speed responsive means for varying the free area through said restriction in accordance with variations in the speed of said pump to maintain a pressure differential across said restriction proportional to intake air density regardless of pump speed, a controllable displacement engine driven fuel supply pump, and a fluid pressure responsive device pneumatically connected with said restricted fluid pump connection at opposite sides of said restriction and operatively connected with said fuel supply pump to regulate the displacement of said fuel supply pump in accordance with variations in the density of the engine intake air.

3. The arrangement as set forth in claim 2 in which the engine is provided with a throttle and one or more cylinders and one side of said fluid pump is connected to the engine air induction system between said throttle and said cylinder.

4. A fuel-metering device for an internal combustion engine having an air induction system and a fuel injection device comprising, an engine driven pump having a definite volumetric capacity for each operating speed connected at both sides to said air induction system, an orifice of predetermined maximum area in the connection between one side of said pump and said air induction system, movable means for varying the area of said orifice, means responsive to pump speed for controlling the movements of said movable means to maintain a pressure differential across said orifice proportional to the density of the air flowing therethrough regardless of

variations in pump speed in the operative range of the device, an engine driven controllable displacement fuel supply pump, and a fluid pressure responsive device actuated by said pressure differential and operatively connected with said fuel supply pump to vary the displacement of said fuel supply pump in accordance with variations in said pressure differential.

5. In combination, a fluid conduit, a fluid pump in said conduit having a definite volumetric capacity for each operating speed, a variable area orifice in said conduit, means for driving said pump, means for varying the area of said orifice in accordance with the speed of said pump, and 15 a device connected with the spaces at opposite sides of said variable area orifice operated by the pressure difference across said orifice comprising, a controllable displacement pump and a fluid pressure responsive device for varying the capacity of said pump in accordance with variations in said pressure difference.

6. The arrangement as set forth in claim 2 including a manually controllable air bleed between the opposite sides of said fluid pressure actuated device to provide a manual mixture control for said fuel supply system.

7. The arrangement as set forth in claim 4 in which said movable means for varying the area of said orifice is provided with a curved orifice varying portion for varying said orifice area at a rate proportional to variations in the volumetric efficiency of said engine in addition to variations proportional to changes in pump speed.

8. The arrangement as set forth in claim 4 including a specially shaped portion on said means for varying said orifice area at a predetermined rate in addition to variations proportional to changes in pump speed to vary the fuel-air ratio of the mixture supplied to the engine at at least one end of the quantitative range of fuel supply.

9. The arrangement as set forth in claim 4 including means for varying the area of said orifice operative to vary said orifice area in proportion to variations in the volumetric efficiency of said engine over the engine speed range and in accordance with a predetermined fuel to air ratio at different points in the quantitative fuel supply range in addition to said variation proportional to changes in engine speed.

10. In combination with an engine having an air intake duct, and a power regulating throttle, means for continuously sampling the air in said air intake duct between said engine and said throttle during engine operation and providing a pressure head proportional to the product of the density of said air and the volumetric efficiency of said engine, and pressure responsive indicating means actuated by said pressure head and calibrated to continuously disclose the indicated mean effective pressure of the gas in the cylinders of said engine during engine operation.

11. In combination with an engine having a restricted passage through which intake air is forced, means for maintaining the flow rate through the restricted passage so that the pressure differential across the restriction varies in accordance with changes in intake air density, means for injecting fuel into said intake air, means for measuring the quantity of fuel injected, and means actuated by said pressure differential for adjusting said measuring means to maintain the correct proportion of fuel to air for different intake air densities.

12. In combination with an engine having a

restricted passage through which intake air is forced, means for maintaining the flow rate through the restricted passage such that the pressure differential across the restriction varies in accordance with changes in intake air density, an engine driven variable volume pump for injecting fuel into said intake air, and a device actuated by said pressure differential across said restricted passage for changing the volume per revolution capacity of said pump in accordance with changes in intake air density.

13. In combination with an engine having a restricted passage through which intake air is forced, means for maintaining the flow rate through the restricted passage so that the pressure differential across the restriction varies in accordance with changes in intake air density and engine volumetric efficiency, means for injecting fuel into said intake air, means for measuring the quantity of fuel injected, and means actuated by said pressure differential for adjusting said measuring means to maintain the correct proportion of fuel to air for different intake air densities and for changes in engine volumetric efficiency.

14. In combination with an engine having a restricted passage through which intake air is forced, means responsive to changes in engine speed for varying the free area of said restricted passage, said means constructed and arranged so that the pressure differential across the restriction varies in accordance with intake air density and a speed induced engine variable, such as volumetric efficiency, means for injecting fuel into said intake air, means for measuring the quantity of fuel injected, and means actuated by said pressure differential for adjusting said measuring means to maintain the correct proportion of fuel to air for different intake air densities, and different engine speeds.

15. Charge forming apparatus for an internal combustion engine having an air intake system and a variable capacity fuel supply means having a driving connection with said engine comprising, engine driven means for continuously forcing a sample of intake air through a restricted orifice, speed responsive means for varying the restriction of said orifice in accordance with variations in engine speed, and means actuated by the pressure drop across said orifice to regulate the output capacity of said fuel supply means in accordance with variations in said pressure drop.

16. Charge forming apparatus for an internal combustion engine having an air intake system and an engine driven fuel supply means the output capacity per operating cycle of which is adjustable, a pneumatic shunt circuit having a restriction therein connected at both sides to said air intake system, an engine driven pump having a constant volumetric capacity for each operating cycle interposed in said circuit for continuously forcing a measured quantity of intake air therethrough, speed responsive means for varying the magnitude of said restriction in direct proportion to variations in engine speed, and a pneumatic device connected with said shunt circuit and with said fuel supply means and actuated by variations in the pressure drop across said restriction to vary the output capacity of said fuel supply means in direct proportion to variations in said pressure drop.

17. Charge forming apparatus for an internal combustion engine having an air intake system

and a fuel supply means comprising, an intake air sampling device including a casing comprising two chambers connected independently with said air intake system and separated by a transverse partition having an air flow orifice therethrough, a positive displacement engine driven pump interposed in the connection between one of said chambers and said air intake system to maintain a circulation of engine intake air through said chambers and said orifice, means for compensating said air sampling device for variations in engine speed, and a pneumatic device connected with said chambers and with said fuel supply means and actuated by changes in the pressure differential between said chambers to vary the output capacity of said fuel supply means in accordance with variations in the pressure differential across said orifice.

18. In combination with an engine having a restricted passage through which intake air is forced, means for maintaining the flow rate through the restricted passage so that the pressure differential across the restriction varies in accordance with changes in intake air density, means for injecting fuel into said intake air, means for measuring the quantity of fuel injected, a fluid pressure responsive device actuated by said pressure differential and operatively connected with said measuring means for adjusting said measuring means in accordance with variations in said pressure differential, and means for providing a time lag in the application to said fluid pressure responsive device of sudden changes in the pressure differential across said restriction.

19. Fuel control means for an internal combustion engine comprising, a variable capacity fuel supply device, means for determining variations in the product of the engine intake air density and the volumetric efficiency of the engine, and means responsive to the operation of said determining means for varying the capacity of said fuel supply device in proportion to said variations.

20. Fuel supply means for an internal combustion engine comprising, a variable capacity fuel supply device the capacity of which tends to vary directly with variations in engine speed, means for continuously evaluating the product of engine intake air density and the volumetric efficiency of said engine, and means responsive to the operation of said evaluating means for proportioning the capacity of said fuel supply device to said product.

21. In an engine charge forming apparatus, an engine driven adjustable displacement fuel pump, an air sampling device for continuously passing a sample of engine intake air through a restriction and having means operative to maintain a predetermined ratio between the volumetric flow rate of the sample air and the size of the restriction to provide across said restriction a pressure head proportional to the density of said intake air, means actuated by said pressure head and operatively connected with said fuel pump for varying the quantity of fuel delivered per cycle by said pump in accordance with variations in intake air density to maintain a substantially constant proportion between the weight of intake air and the weight of fuel delivered to said engine in the same interval, and manually operated means for varying said pressure head.

DONALD S. HERSEY.
